UNITED STATES PATENT OFFICE.

FRANKLIN H. CONEY, OF CHICAGO, ILLINOIS.

CONCRETE BUILDING.

Application filed February 11, 1922. Serial No. 535,675.

To all whom it may concern:

Be it known that I, FRANKLIN H. CONEY, a citizen of the United States of America, and a resident of Chicago, county of Cook, 5 and State of Illinois, have invented a new and useful Improvement in Concrete Buildings, of which the following is a specification.

This invention relates to flat slab construction and particularly to column caps designed to reinforce, support and be a part of the floor slab in the area adjacent to the supporting column. An object of the invention is to provide a column cap of increased 10 strength with respect to its dimensions whereby it is possible to avoid the loss of space resulting from the necessity of using flaring column heads or the depressed heads surrounding each column. A further object 15 is to simplify the form structure making it less expensive, and further to permit the use of steel columns where a smaller diameter column is desired. Another object of the invention is to provide a completely connected skeleton of steel upon which the 20 forms may be supported and which becomes a part of the completed structure.

The objects of the invention are accomplished by the device shown in the accompanying drawings, wherein—

Figure 1 is a plan view of the improved column cap showing a column in section, and the floor reinforcing bars which are secured to the cap.

Fig. 2 is a side elevational view of the column cap showing portions of a floor and upper and lower columns.

Fig. 3 is a sectional detail of a column taken on the line 3—3 of Fig. 2.

Figs. 4 and 5 are respectively views like Figs. 1 and 2, but show the invention as used in connection with steel columns.

The invention is carried out by means of a column cap, which may be of various forms, such as a cast steel plate with ribs, a solid cast plate or built-up plate consisting of several plates riveted or welded together, but is here shown as preferably comprising a pair of spaced plates with spacers or web members between these plates. The column caps are secured to the upper ends of columns, but where two columns are in coaxial relationship, the cap between the same is secured to both. In the cap as shown, the 55 tension stresses are taken by the top part of the cap, and the compression stresses are

taken by the bottom part. The tension stresses are greatest at the top surface of the top plate, and diminished to zero at the neutral plane dividing the top and bottom parts, 60 the compression stresses being greatest at the bottom surface of the bottom plate, and diminishing upward to zero at the same neutral plane. The maximum shearing stresses take place within the area of the cap, and 65 are therefore taken by this cap. The column caps of each floor are preferably connected by small I-beams where steel columns are used in order to afford rigidity to the entire structure and supports for the temporary 70 forms for the concrete. The edges of the plates are perforated to receive the bent ends of reinforcing bars, and both plates are provided with a plurality of filling apertures 75 so that concrete may be poured into the spaces between and below the plates of the cap.

Since the stresses in a floor slab of the kind illustrated are greatest over the point of support, in this case the column, the column cap is designed to suitably resist these stresses within its area. Since the cap is provided with means for attaching thereto all reinforcing bars that intersect it, the structure affords high resistance to 80 shifting of these bars. The tensile stresses in the rods in the top of the slab at the point of attachment to the cap are transferred to the top plate, being the same in effect as though the rods were continuous across the 85 area of the cap. The compression stresses in the concrete and rods in the lower part of the slab at the edge of the cap and point of attachment of the rods are transferred to the bottom plate, the effect being the same 90 as though the rods and concrete were continuous across the area of the cap.

The drawings show coaxial floor supporting columns 1 and 2 between which extends the plate reinforcement 3. This reinforcement or column cap may be secured to the columns when steel columns are employed by the bolts or rivets 4, attached to the flange or L-shaped plates 5 which are also riveted to the plates 6 and 7 forming the column cap. The plates are spaced apart by solid metallic blocks or web members 8 so arranged as shown in Figure 1 to give the necessary strength to the column caps, and these caps extend outwardly from the columns into the floor 9 over the area which should resist the greatest shearing effort. 100 105 110

The upper plate 3 is provided with openings 10 through which concrete may be poured into the spaces between the spacing blocks 8. Near the edges of each plate 6 and 7 are 5 perforations 11 and through which extend the bent ends of the reinforcing bars 12. Many of these bars extend from one column cap to another, but some are short as indicated in the drawing, and all are arranged 10 in the usual most approved way to reinforce the floor and properly resist the strains to which the floor is subjected by its weight and load.

The I-beams 13 are secured to the column 15 caps through the plates 14 riveted thereto, and while the I-beams are not always employed, when they are used they assist in affording good supports for concrete forms and in making a fairly rigid completely connected steel skeleton for a concrete building.

The construction as illustrated requires only the simplest forms to retain the concrete when poured to form the column and floors, and avoids the labor, space and expense of beams and flaring or depressed column heads.

Where concrete columns of the type illustrated in Figures 1 and 2 are used, holes must be provided in the column caps for 30 the reinforcing rods of the column to pass through. These reinforcing rods 16 as shown in Figure 2 are arranged so that the rods of the lower column pass upwardly and overlap the rods of the upper column 35 for a short distance. The rods 16 for the upper column terminate at their lower ends in the plane of the surface of the floor.

To offset the tendency to bend of concrete columns having an eccentric load, and 40 to resist bending of the column due to pressure of wind the short reinforcing rods 17 are employed. These pass through holes in the metallic column cap, some depending from the cap and extending into the lower 45 column and others extending upwardly into the upper column. The ends of these reinforcements are bent as indicated at 18 to hook over the plates 3. If the floor has an excess load, for instance, at the left of the 50 column, Figure 2, then the rods 17 at the left of the column would act to resist the bending movement in the column, and the rods 18 on the right side of the column

would not be required except to cooperate with all the rods to resist wind pressure.

Although but one specific embodiment of this invention is herein shown and described, it will be understood that numerous details of the construction shown may be altered or omitted without departing from the spirit 60 of this invention as defined by the following claims.

I claim:

1. A concrete building comprising reinforced columns and flooring, and reinforcing plates forming part of the flooring and located at the columns, and to which floor reinforcing bars are attached, the reinforcements in the column including short bars which pass through said plate and some of 70 which bars extend upwardly and some downwardly into the columns, and all having their ends at the plate bent over.

2. A column cap for concrete buildings, comprising a pair of horizontally disposed 75 metal plates one above the other, spacers or shear members between said plates, means for securing said cap to a column, and said plates having provision for attachably receiving floor reinforcing bars.

3. A column cap for concrete buildings, comprising a pair of horizontally disposed metal plates one above the other, spacers or shear members between said plates, means for securing said cap to a column, said 85 plates having provision for attachably receiving floor reinforcing bars, and both of said plates being provided with concrete receiving openings.

4. A column cap of the class described 90 comprising spaced upper and lower plates with web members between said plates, said upper and lower plates of the cap having provisions for attachably receiving floor reinforcing bars.

5. A column cap of the class described comprising spaced upper and lower plates with web members between said plates, said upper and lower plates of the cap having provisions for attachably receiving floor reinforcing bars, and horizontally disposed I-beams attached to said plates.

Signed at Chicago this 9th day of February 1922.

FRANKLIN H. CONEY.
